United States Patent Office

Des. 192,286
Patented Feb. 27, 1962

192,286

CEILING PANEL

Carroll S. Delaney and De Forrest R. Roggenbach, Denver, Colo., assignors to De-Arco Diagrid Company, Denver, Colo., a business association

Filed May 2, 1960, Ser. No. 60,397

Term of patent 7 years

(Cl. D13—1)

FIG. 1.

FIG. 3.

FIG. 2.

FIG. 4.

FIGURE 1 is a perspective view of the ceiling panel showing our new design as it would appear on a ceiling, the sides and top being planar and devoid of ornamentation;

FIGURE 2 is a bottom plan view thereof;

FIGURE 3 is a side elevation thereof; and,

FIGURE 4 is a cross-sectional view taken on line 4—4 of FIGURE 3.

We claim:

The ornamental design for a ceiling panel, as shown and described.
